(57) **CLAIM**

The ornamental design for a tire, as shown and described.

DESCRIPTION

FIG. 1 is a perspective view of the tire of my design; FIG. 2 is a front elevation view of the tire of my design; FIG. 3 is a side elevation view of the tire of my design; FIG. 4 is a side elevation view of the tire of my design, taken from the opposite side of that shown in FIG. 3; and, FIG. 5 is an enlarged, partial view of the tire of my design, as indicated by the break lines.

The dash-dot-dot lines define the peripheral boundaries of the claim. The broken line disclosure in the drawings depicts environmental subject matter forming no part of the claimed design.
